MATCH CONTAINER

Bertis Hamilton, Columbus, Ind.

Application May 26, 1933, Serial No. 672,924

1 Claim. (Cl. 206—30)

It is the object of my invention to produce a device which will contain a supply of matches, which will render those matches readily available one at a time, and which will embody a safe 5 container for burnt matches.

In carrying out my invention, I provide a box of incombustible material, such as sheet-metal, divided into two compartments by a vertical partition, one of such compartments being intended to contain unused matches and the other 10 burnt matches. Unburned matches are supported in their compartment by a yielding means which will permit them to be withdrawn from the bottom of the compartment one at a time. The 15 other compartment is provided with a slot in its top through which burned matches can be dropped. Associated with this opening are baffles which obstruct the ready flow of air through the slot and insure that any match dropped into 20 the burned-match compartment while still ignited will be promptly extinguished for want of oxygen.

The accompanying drawing illustrates my invention: Figs. 1 and 2 are front and side elevations 25 respectively of the match container with parts thereof broken away; and Figs. 3 and 4 are top and bottom plan views respectively of the container.

Conveniently, the body of the container is 30 formed of two pieces of sheet metal one of which is bent to form a front wall 10 and side walls 11 and the other of which constitutes the back wall 12, the latter piece being provided along its vertical edges with flanges 13 which overlap the rear edges 35 of the side walls 11 and may be secured thereto as by spot-welding. The box is divided internally into two compartments by means of a vertical partition 14 having along its edges flanges 15 adapted to be spot-welded or otherwise secured to 40 the front and back walls 10 and 12 respectively of the box. The burned-match compartment, which is shown in Fig. 1 as lying to the left of the partition 14, is provided with a bottom 16 conveniently formed integrally with the partition 14 and bent at right angles thereto. Flanges 17 along the edges of the bottom 16 provide for its attachment to the walls of the box.

In the compartment for unused matches, there 45 is secured to the back wall 12 of the box a sheet-metal bracket 20 having an inwardly and downwardly bent flange 21 to which are secured, near opposite sides of the compartment, forwardly and downwardly extending spring fingers 22 the free ends of which lie close to the rear face of 50 the front box-wall 10. This front wall 10 of the

box is provided near the center-line of the unused-match compartment with a notch 23 which extends upwardly to a point above the free ends of the fingers 22. Matches disposed horizontally within the unused-match compartment are supported by the spring fingers 22 which, at their free ends, are provided with generally horizontal lips 24 of a width approximating that of a match. When matches are in the unused-match compartment, one match will rest upon the lips 24 10 and will extend across the notch 23 so that it can be grasped between the thumb and forefinger and withdrawn downwardly. The elastic character of the spring fingers 22 permits such fingers to bend and thus permits the grasped match to be 15 withdrawn. Upon disengagement of the match from the ends of the fingers 22, these fingers return to the position illustrated in Fig. 2, the lip 24 20 engaging the next match and holding it in position for withdrawal.

For the box I provide a cover 25, conveniently 25 formed of sheet-metal, and having at its edge flanges 26 which overlie the upper edges of the box-body. Above the burned-match compartment the cover 25 is provided with a slot 27 through which burned matches may be dropped. To prevent the free flow of air through the slot 27, there are associated with it baffles, as indicated in Fig. 2. Conveniently, one of these baffles is constituted by a tongue 28 defined by a U-shaped cut in the cover 25 and bent downwardly to an inclined position to provide the slot 27. The other baffle may be a separate piece of sheet-metal bent along longitudinal lines to provide an upper portion 29 adapted to be secured against the under side of the cover, an intermediate portion 30 extending obliquely downwardly to a point adjacent the lower edge of the tongue 28, and a third portion 31 which extends across the free edge of the tongue 28 at a lesser inclination. 30

The baffles formed by the tongue 28 and the inclined walls 30 and 31, as indicated, prevent the ready flow of air through the slot 27, and in addition tend to extinguish any match which may be inserted in the slot 27 while still ignited. 35 To insure against the possibility of matches burning in the burned-match compartment, the joints between the bottom 16 and the walls of the box-bottom may be sealed, as by soldering. 40

For the purpose of striking matches a rough 45 surface may be provided on the bottom 16 of the burned-match compartment. Such a rough surface may be formed by a piece of steel gauze or screen 35 soldered or otherwise secured to the lower surface of the bottom 16. 50

For the purpose of mounting the match container upon a wall I may secure to the back wall 12 thereof two spaced horizontally extending strips 36, the center portions of which are offset 5 outwardly to permit the reception of ears 37 stuck up from a vertical bracket 28 adapted to be secured to the wall on which the match-box is to be mounted.

Preferably, the unused-match compartment is 10 of a size such as will snugly receive the cardboard boxes in which matches are customarily sold. By tearing out the end of such a cardboard box and by inserting it in the unused-match compartment with the torn-out end toward 15 the bottom of the compartment, the entire supply of matches in the box may be quickly and easily transferred to the unused-match compartment to

be withdrawn therefrom one at a time as previously indicated.

I claim as my invention:

A device of the class described, comprising a box having an open upper end, a removable sheet-metal cover for the open end of said box, said cover being provided with a generally U-shaped slot defining a tongue, said tongue being bent downwardly to create an opening through the cover and to occupy a downwardly inclined position when the cover is in place on the box, and a baffle of sheet-metal secured to the lower side of said cover on the side of such opening opposite said tongue, said baffle occupying a downwardly inclined position and extending beyond but spaced 10 from the lower longitudinal edge of said tongue. 15

BERTIS HAMILTON.
